UNITED STATES PATENT OFFICE.

DAVID L. LINDQUIST, OF HARTSDALE, NEW YORK, ASSIGNOR TO OTIS ELEVATOR COMPANY, OF JERSEY CITY, NEW JERSEY, A CORPORATION OF NEW JERSEY.

ELEVATOR SAFETY APPLIANCE.

Application filed July 11, 1924. Serial No. 725,429.

To all whom it may concern:

Be it known that I, DAVID L. LINDQUIST, a subject of the King of Sweden, residing in Hartsdale, in the county of Westchester and 5 State of New York, have invented a new and useful Improvement in Elevator Safety Appliances, of which the following is a specification.

This invention relates to safety devices 10 for the parts of an elevator system traveling in the hatchway, and particularly to safety brakes adapted to be applied to a stationary rail for bringing the moving parts to a stop in the event of their traveling above predetermined speeds or too far beyond their 15 upper and lower limits of travel.

One object of the invention is to apply a substantially constant retarding force in predetermined amount to bring the moving 20 parts to a stop whenever the safety device is actuated.

Another object is to provide a safety 25 brake which after it has been applied to stop the moving parts will be released upon their being moved in the reverse direction.

A further object is to provide means for 30 applying the safety brake when the moving parts have reached a predetermined point in the hatchway regardless of their speed.

35 A further object is to provide means for applying the safety brake should the retardation of the elevator car in approaching a terminal landing be insufficient to bring it to a stop within the normal limits of travel.

40 A further object of the invention is to provide flexible guide shoes for the moving parts which guide shoes will yieldingly engage the guide rails.

45 Other objects will appear from the specification and claims.

In a preferred embodiment of the invention the safety brake, which is mounted on the elevator car, has a pair of brake shoes disposed on opposite sides of the guide rail and arranged to be brought into engagement with the guide rail when the safety brake is applied. The brake shoes are pivotally mounted on links, which, in 50 connection with the rocking jaws, act to exert a pressure between the shoes and the rail. The amount of such pressure is automatically regulated by an adjustable re-

silient force acting substantially parallel to the rail, and this resilient force determines the retarding effort. The organization of parts is such that when the car has been brought to rest by the safety brake on the guide rail of normal thickness, it can be started in the opposite direction by the hoisting mechanism, without the necessity of first manually disengaging the parts of the safety brake from the rail. A governor is provided for applying the safety brake in the event that the moving parts should travel above a predetermined speed along their path of travel. Means are provided for applying the safety brake to stop the car in the event that the speed of the car has not decreased to a predetermined speed when the car is at a given distance from its lowest stopping point and means are provided for applying the safety brake in the event that the elevator car continues to travel below the said stopping point. Means are also provided for applying the safety brake in the event that the car travels above its highest stopping point. This latter is accomplished by employing a guide rail having an increased thickness at its upper end which will be engaged by the brake shoes as they pass upwardly upon this section of the rail. In this event the safety 70

brake will be applied under a resilient force acting oppositely to the before mentioned resilient force and in such a manner as to lock the elevator car until the safety brake has been manually released. The elevator car is provided with flexible guide shoes which will yieldingly engage the rails throughout their length for properly guiding the car and which will permit of the car passing along a portion of the rail having an increased thickness.

In the accompanying drawings,

Figure 1 is a schematic view of an elevator system to which safety devices in accordance with this invention are applied,

Figure 2 is a front elevation on a larger scale of a portion of the rail used in the elevator system shown in Figure 1,

Figure 3 is an end elevation of the safety brake in released position and shows operating mechanism therefor,

Figure 4 is a sectional view taken on line 4-4 of Figure 3,

Figure 5 is an elevation of the safety brake in applied position on a portion of the rail of normal thickness.

Figure 6 is an elevation of the safety brake in applied position on a portion of the rail of increased thickness, and

Figure 7 is a sectional view taken on line 7-7 of Figure 3.

Referring to Figure 1, the elevator system includes a car 10 which is suspended by cables 11 extending over a hoisting drum 12 to counterweight 13. The drum 12 is driven by a motor 14 and has an electromagnetic brake 15. Stationary guide rails 16 are provided and the car 10 has an upper set of guide shoes 17 and lower set of guide shoes 18 which engage rails 16. The thickness of the guide rails is increased above the point 19, Figure 1, in the manner shown in Figure 2 for a purpose to be hereinafter pointed out.

Safety brakes 20 are mounted one on each end of a safety plank 21 which is secured to the bottom of the car. Two governors, 22 and 23, operate to apply the safety brakes under certain conditions, and a cam 24 in the elevator pit acts to apply the safety brake in the event that the car should travel below its lowest landing.

Governor 22 is driven by the car through a governor rope 25. A hitch 26 is fastened to rope 25 and is normally held in a releasing carrier 27 attached to the elevator car. This governor is provided with jaws 28 and 29 which are adapted to grip the governor rope 25 in the event that the governor is tripped due to an excessive speed. Jaws 28 and 29 have a gear connection between them so that they will operate together. Jaw 28 is pivoted at 30 and is provided with an arm 31 to which a link 32 of the governor is operatively attached. A spring pressed latch 33 engages the end of arm 31 until such a time as the governor reaches the speed for which it is adjusted to act whereupon latch 33 releases arm 31. When arm 31 is released link 32 raises arm 31 so as to close jaws 28 and 29 upon the governor rope 25 and thus stop its movement. Jaw 29 is pivotally mounted at 34 on a rod 35 which is slidably carried in a guide support 36 and provided with a spring 37 which urges the jaw 29 into engagement with the governor rope 25 but allows rope 25 to slide through the jaws when the tension exceeds an amount determined by the pressure of spring 37. When the governor acts due to overspeed of the car in the down direction, hitch 26 is withdrawn from releasing carrier 27 and as the elevator descends a tension is exerted on a rope 38 to apply safety brakes 20 to rails 16 as will hereinafter be set forth.

Governor 23 is provided with a governor

rope 39 which is fastened at 40 to the elevator car so as to operate the governor in accordance with the speed of the car. This governor is adapted to project a cam 41 outwardly into the elevator hatchway for applying the safety brake in the event that the elevator car should travel over a predetermined speed as it approaches its lowest landing 42. Cam 41 is secured on one end of a rod 43 slidably mounted in supports 44. The other end of rod 43 is connected with an end of toggle 45 which is pivotally secured at its other end to an abutment 46. A link 47 connects toggle 45 with a lever 48 which is operated by governor 23 which operates to straighten the toggle when the governor is operating above a predetermined speed. Two spring catches 49 and 50 are mounted on link 47 which are adapted to be engaged by spring pressed latches 51 and 52 on a stationary support 53. Catch 49 is adapted to pass latch 51 when the governor operates above a certain speed and to be engaged thereby until the speed has decreased to a speed which is not excessive for the moving parts of the elevator system when the car is running in the hatchway in the vicinity of the lowest landing. Catch 50 and latch 52 are operative to hold the cam in its retracted position, as shown in Figure 1, until the speed of the car, and consequently the governor, has increased above the speed at which the elevator normally travels when it passes cam 41 in running upwardly from its lowest position in the elevator hatchway. When this speed has been exceeded the latch releases and allows the governor to project cam 41 outwardly into the hatchway. The operation of cams 41 and 24 to apply the safety brakes 20 will be hereinafter set forth.

Referring to Figure 3, the safety plank 21, upon which safety brakes 20 are mounted, comprises two channels 54 and 55 secured in spaced relation by means of upper and lower plates 56 and 57 respectively. Abutments 58 are secured to the channels at their ends on opposite sides of the guide rails 16 and are provided with lower projections 59 for guiding actuating rods 60 for the jaw members 61 and 62.

The abutments 58 are each provided with projecting ears 63 and bolts or pivot pins 64 passing through these ears and the jaw members 61 and 62 afford pivotal connections for carrying the jaw members on the abutments. The jaw members are free to swing on the pivot pins 64 between adjustable spring stops 66 carried by the lower projections 59 and adjustable fixed stops 65 comprising bolts which pass through the abutments 58 and the channel members 54 and 55. The spring stops 66 comprise bolts having springs 67 and nuts 68 which engage

the ends of the bolts extending through the projections 59. The nuts 68 serve the purpose of adjusting the position of the stops for the jaw members in their released position.

Between each of jaw members 61 and 62 and the rails 16 is a brake shoe 69. The shoes 69 are mounted on links 70 which extend between them and the jaw members. 10 The ends of the links are rounded and fit in corresponding cylindrical bearings formed in recesses in the jaw members 61 and 62, and in the brake shoes 69. It will be noted that the upper and lower walls of 15 these recesses are cut away to permit rocking movement of the links with respect to the jaw members and the brake shoes with respect to the links. The lower walls 71 of the recesses in the jaw members project 20 slightly and perform the function of stops for limiting the downward rocking movement of the links 70.

The links 70 are pivotally connected at their ends with the jaw members and with 25 the brake shoes. Referring to Figures 3 and 4, a side plate 72 is shown secured on each side of jaw member 62, by screws 73. These side plates overlap the ends of links 70 and have pivotal connections thereto by 30 pins 74. The opposite ends of links 70 are provided with slots 75 which receive webs 76 extending lengthwise of shoes 69 in the recesses in them. Pivot pins 77 connect the links 70 with the brake shoes 69 by passing 35 through the ends of links 70 and webs 76 of the brake shoes. The axes of the pins 74 and 77 are coincident with the axes of the cylindrical bearings for the ends of the links. The arms of yoke 78 are pivoted on 40 pins 77 and pass around the upper portion of the brake shoes. The outward thrust of the brake shoes is transmitted to the jaws through the cylindrical bearings and links 70 so that the plates 72 and pins 74 are not 45 called upon to transmit this thrust, but serve to hold the parts assembled. Springs 79 urge the brake shoes 69 downwardly about pins 74 in the jaw members 61 and 62, so that the links 70 are in engagement with 50 projections 71 of the jaw members. Springs 79 are positioned between the yokes 78 and a projection 80 on the upper end of the jaw members and adjusting screws 81 serve to regulate the pressure exerted by springs 79.

55 In using the safety brakes 20 in conjunction with guide rails having an increased thickness for a portion of their length, the car is provided with flexible guide shoes 17 and 18 which will accommodate themselves 60 to the different thicknesses of the guide rails. These flexible guide shoes adjust themselves to any unevenness of the rails and provide a smoother operation of the elevator car in the hatchway.

65 The construction of the guide shoes is

shown in Figures 3, 6 and 7. Channel 84 is secured to the upper cross plate 56 of the safety plank by means of bolts 82 extending through projections 83 on cross plate 56 and channel 84. Channel 84 provides a support 70 for the shoes 85 which engage the sides of rail 16. These shoes are provided with bolts 86 which extend through apertures in the channel, and outside of the channel the bolts are provided with adjusting nuts 87 and lock nuts 88 for limiting the inward movement of the shoes. Springs 89 are positioned on the bolts 86 between the shoes 85 and the channel 84 for yieldingly pressing the shoes 85 toward the rail. The channel is further provided with a spring pressed guide plate 90 which engages the inner edge of rail 16. Plate 90 is supported on the back of the channel by means of bolts 91 passing through it and the channel, and on these bolts between the plate and the channel are springs 92. Bolts 91 are provided with adjusting nuts 93 and lock nuts 94 so that the plate can be adjusted with respect to the distance between the guide rails. 99

The actuating mechanism for the safety brake comprises rods 60 arranged so as to pass vertically upward through projections 59 of the abutments 58. Rods 60 are adapted to be moved into engagement with the lower projections 95 of the jaw members 61 and 62 and to swing them upwardly on their pivotal connections with the abutments 58 until the brake shoes engage the rail 16. Rods 60 are provided with springs 96 positioned between heads 97 on their lower ends and the projections 59 whereby they will be held down away from the jaw members 61 and 62 except when they are moved up by the cams 98. Cams 98 engage the heads 97 of rods 60 and are mounted on the ends of a pair of shafts 99. These shafts are carried by supports 100 extending from the bottom of safety plank 21 and are connected by a pair of gears 101 so as to be rotated together. A beveled gear 102 is secured to the back of one of gears 101 to be driven by a corresponding beveled gear 103 secured to a shaft 104. Shaft 104 is supported by two hangers 105 and 106 and it is provided with a torsion spring 107 which tends to hold it in the released position shown in 105 Figures 1 and 3. Shaft 104 also has a lever 110 arm 108 to which is connected a rope 38 and a link 110. 115

The rope 38 extends from lever arm 108 and passes over a sheave 111, supported to one side of the elevator car, and from there rope 38 extends to the hitch 26 to which it is connected so as to operate the safety 120 brakes from governor 22.

The link 110 connected with lever arm 108 extends to a lever 112, which lever is connected by means of a pivot 113 to a support 114 extending from the bottom of the ele- 125

vator car. Lever 112 has its upper arm 115 extending beyond the side of the elevator car and is provided with a roller 116 which is adapted to engage the cam 41 for actuating the lever for applying the safety brakes by means of governor 23, or to engage the cam 24 for applying the safety brakes.

The operation of the safety brakes is as follows. Assuming that the elevator car is traveling downward at an excessive speed, governor 22 trips, and jaws 28 and 29 grip the governor rope 25, to bring it to a stop. Hitch 26 is withdrawn from carrier 27 and, as the car proceeds downwardly, rope 38 acting through lever arm 108 rotates shaft 104 against spring 107. The rotation of shaft 104 causes rotation of shafts 99 through gears 103, 102 and 101. Cams 98 raise actuating rods 60 against springs 96. As rods 60 move upwardly they engage the projections 95 on the jaw members 61 and 62, rocking these members on their pivots 64 upwardly from their position in Figure 3 until the brake shoes 69 are brought into frictional engagement with rail 16. Due to the friction, jaws 61 and 62 rock upwardly about their pivots 64 while at the same time shoes 69 swing upwardly on links 70 about pins 74 and thereby compress springs 79. The jaws, links and shoes are so proportioned and the relative positions of their pivotal points so selected that the compound motion of the parts results in a gradual increase of friction or retarding force until the portion 117 of the jaws come into engagement with the stops 65. The parts are then in the positions shown in Figure 5 and the safety brake is applied. Were the retarding force to become greater, springs 79 would compress, thereby permitting the brake shoes 69 to move away from rail 16 by swinging on links 70. Such movement would decrease the pressure acting to hold the brake shoes against the rail and consequently the retarding force. The retarding force of the brake shoes may be varied by adjusting the positions of stops 65 and the pressure of springs 79 by means of the screws 81, and this retarding force will remain substantially constant for any adjustment, independent of the condition of the rail or surfaces of the brake shoes.

In applying the safety brakes, rope 38 rotates shaft 104 through an angle of 90° and when lever arm 108 has reached a horizontal position, rope 38, acting through hitch 26, draws the governor rope 25 through jaws 28 and 29 until the elevator stops. When it is desired to reset the mechanism, jaws 28 and 29 are manually released from rope 25 and latch 33 is reset. Hitch 26 is replaced in the releasing carrier 27 on the elevator. Spring 107 operating upon shaft 104 rotates the cams 98 from the position shown

in Figure 5 to that shown in Figure 3. Movement of the car 10 in the up direction will return the brake shoes 69 to their lower position and thereby effect a release of the safety brakes.

It is to be noted that governor 22 operates to apply the safety brakes in the event of an excessive speed of the elevator car in a downward direction in any part of the elevator hatchway in the manner above set forth.

Governor 23 is provided to apply the safety brakes in the event that the elevator car should fail to get the proper slow-down as it approaches the lower landing 42, as for instance, in case the power supplied to the hoisting motor should be interrupted. The operation of this governor in applying the safety brakes under these conditions is as follows. Cam 41 is projected outwardly into the hatchway by the governor 23 while the elevator car is running at full speed in either direction in the hatchway, and the cam is maintained in such a position by the toggle mechanism, catches, and latches previously described. In the normal operation of stopping, the speed of the elevator car will have decreased sufficiently by the time roller 116 passes the point at which cam 41 is located to insure cam 41 being retracted by governor 23. In the event that the car is not at a sufficiently low speed in this position, cam 41 will be held out and be engaged by the roller 116 on lever 112 and thereby tilt this lever. Link 110 acting on lever arm 108 applies the safety brakes by the turning of the shaft 104 and shafts 99 with their cams 98 as already described. As the car is stopped roller 116 may have run off the lower end of cam 41 so that lever 112 and the operating mechanism connected therewith return to the position shown in Figure 1 and 3.

In order to allow the elevator car to travel up the hatchway without applying the safety brakes, the catch 50 and latch 52 serve the function of retaining the governor elements in a position so that cam 41 will be held in retracted position until the elevator car has attained a certain speed. In the normal operation of the elevator system the elevator car does not accelerate to a speed sufficient to effect a release of the catch 50 before roller 116 has passed cam 41.

In the event that the elevator car should continue to travel below the lower landing by more than a predetermined distance, roller 116 will engage cam 24 and apply the safety brakes in the same manner as cam 41 to bring the car to a stop.

After the safety brakes have been applied by either cam 41 or cam 24, they may be released by moving the elevator car upward and the brake shoes will drop to their inoperative position as shown in Figure 3.

Governor 23 does not require manual resetting as in the case of the actuation of governor 22, but is automatic in its action as previously described.

5 To prevent cam 24 from actuating the safety brakes upon operation of the elevator car in the up direction after roller 116 has passed the cam in the down direction, it is pivoted at 118 and rests upon a stop 119 so that when the car is traveling up, roller 116 will engage the portion 120 and raise the cam up out of the path of the roller.

In the event that the elevator car travels in the up direction too far above the top 15 landing, as for example, due to proper slowdown not being obtained, the safety brakes will be applied. The application in this case is accomplished by the shoes engaging the thickened portions of the rails to rock 20 jaws 61 and 62 about pivots 64 against the action of springs 67. (See Figure 6.) The retarding force is determined by the pressure exerted by springs 67 and is substantially constant since, were the friction between 25 the rail and the shoes to become greater, springs 67 would give and permit the shoes together with jaws 61 and 62 to rock about pivots 64. The operation of the safety devices in this instance is independent of 30 the governors.

After the safety brakes have been applied to the rail of increased thickness they operate to hold the elevator in that portion of the hatchway. The safety brakes are not 35 self-releasing on the thickened portion of the rail, and when it is desired to release the safety brakes nuts 68 are turned so as to compress springs 67 until the stops 66 will no longer exert a thrust on the brake shoes. 40 The elevator car may then be operated in an up direction, thereby effecting a release of the brake shoes. When the elevator car has been moved again onto the rail of normal thickness the nuts 68 may be readjusted, so that the stops will perform the 45 functions required.

Although in the foregoing disclosure the safety brakes have been described as mounted on the elevator car, it will be understood that safety brakes may be similarly used in connection with other moving parts of the elevator system.

It is to be noted that the invention provides means for applying a safety brake to stop the car whenever it travels beyond set limits of travel in either direction; also that the safety brake will be applied due to overspeed of the car or in case the normal slowdown has not operated to bring the car to a stop within the limits of its travel; also that the retarding force in the up direction is independent of that in the down direction and either may be of any desired amount. The safety brake may be employed to act

in place of the buffers in the elevator pit or 65 it may be arranged to provide a part of the retarding force for stopping the car, in which event it may be used in conjunction with buffers in the pit.

What is claimed is:—

1. In an elevator system, the combination 70 of a safety brake on a moving part in the hatchway adapted to grip a stationary member along the path of the moving part, and means for applying said safety brake in the event that the moving part should pass beyond its normal limits of travel.

2. In an elevator system, the combination 75 of a safety brake on a moving part in the hatchway adapted to grip a stationary member along the path of the moving part, and means for applying said safety brake in the event that the moving part should pass beyond a predetermined point, said means being inoperative for applying said safety 80 brake upon the reverse operation of the moving part.

3. In an elevator system, a moving part in the elevator hatchway, a stationary member 85 along the path of the moving part, a safety brake on said moving part operable to grip said stationary member when the moving part is operating in one direction, and means for causing the operation of the safety brake in the event that the moving part is operating at or above a predetermined lower than 90 normal speed as a point on said moving part reaches a predetermined point in the hatchway but permitting the continued operation of said moving part without causing the operation of the safety brake in the event that the moving part is operating below said predetermined speed as said point on the moving part reaches said point in the hatchway, 95 said safety brake, when operated, being releasable from said stationary member by the operation of the moving part in the opposite direction.

4. In an elevator system, the combination 100 of a safety brake on a moving part in the hatchway adapted to be applied between its normal limits of travel for retarding the moving part when operating in its down direction and to be released by the operation of the moving part in its up direction, and means for applying said safety brake in the event that the moving part should pass below a predetermined point, said means being inoperative for applying said safety 105 brake upon the reverse operation of the moving part.

5. In an elevator system, the combination 110 of a moving part having a safety brake thereon adapted to be applied upon the moving part exceeding a predetermined speed, and means for operating the safety brake to apply it at a point in the elevator hatchway by movement of the moving part 115

- in one direction, said means being inoperative to apply the safety brake by movement of the moving part in the reverse direction.
6. In an elevator system including a guide rail for the elevator car, the combination of an elevator car having a safety brake thereon adapted to be actuated to grip the elevator guide rail, an actuating means having connections with said safety brake for applying it, and a pivotally mounted cam in the elevator hatchway adapted to engage said actuating means to apply the safety brake by the movement of the elevator car in one direction and adapted to be tilted upon its pivot by said actuating means by movement of the car in the other direction to prevent the safety brake from being applied by the reverse movement of the car.
7. In an elevator system, a moving part in the hatchway, a member carried by and operable to control said moving part, and a cam in the hatchway for causing the operation of said member, upon its engagement with said member with the moving part traveling in one direction, said cam being displaceable by said member, without causing the operation thereof, upon its engagement with said member with the moving part traveling in the other direction.
8. In an elevator system, a moving part in the hatchway, a motor for raising or lowering said moving part, a stationary member along the path of said moving part, a safety brake on said moving part for cooperating with said stationary member, and means for causing the application of the safety brake to said stationary member in the event that the speed of the moving part is not sufficiently reduced as it approaches its normal limit of travel due to the failure of the power supplied to said motor.
9. In an elevator system, a moving part in the hatchway, a stationary member along the path of said moving part, a safety brake on said moving part for cooperating with said stationary member, and means for causing the application of the safety brake to said guide rail in the event that the moving part is operating at or above a predetermined lower than normal speed as a point on said moving part reaches a predetermined point in the hatchway but permitting the continued operation of said moving part without causing the operation of the safety brake in the event that the moving part is operating below said predetermined speed as said point on the moving part reaches said point in the hatchway.
10. In an elevator system, an elevator car, a guide rail, a safety brake on said car for cooperating with said guide rail, and means for causing the application of the safety brake to said guide rail only in the event that the speed of the car is not sufficiently reduced as it approaches a predetermined point.
11. In an elevator system, the combination of a safety brake on the elevator car adapted to cooperate with the elevator guide rail, and means for applying the safety brake to said guide rail in the event that the speed of the elevator car is not sufficiently reduced as it approaches its normal limit of travel.
12. In an elevator system, the combination of a safety brake on a moving part adapted to cooperate with a stationary member along its path, means for applying the safety brake to said stationary member in the event that the moving part travels above one predetermined speed in one portion of its path, and means for applying the safety brake to said stationary member in the event that the moving part travels above another predetermined speed in another portion of its path.
13. In an elevator system, the combination of a safety brake on the elevator car adapted to cooperate with the elevator guide rail, means for applying said safety brake in the event that the elevator car travels at an excessive speed, and means adjacent to the limit of travel of the elevator car for applying the safety brake in the event that the speed of the elevator car is not sufficiently reduced as it approaches said limit.
14. In an elevator system, the combination of a movable cam in the elevator hatchway adapted to be engaged by a moving member when said cam is in its outermost position, and means controlled by the speed of the elevator car for projecting said cam into the path of said moving member and for retracting it therefrom.
15. In an elevator system, the combination of a movable cam in the elevator hatchway adapted to be engaged by a moving member when said cam is in its outermost position, a governor driven by the elevator car, and a connection between the governor and said cam for projecting it into the path of said moving member and for retracting it therefrom according to the speed at which the governor is driven.
16. In an elevator system, the combination of a movable cam in the elevator hatchway adapted to be engaged by a moving member when said cam is in its outermost position, a governor driven by the elevator car, a connection between the governor and said cam for projecting it into the path of the moving member and for retracting it therefrom according to the speed of the elevator car, means for preventing the governor from projecting said cam outwardly until the speed of the car has attained a predetermined speed, and means for preventing the governor from retracting said cam from its

projected position until the speed of the car has decreased to a predetermined speed.

17. In an elevator system, an elevator car, a guide rail therefor, a safety brake on said car operable to grip said guide rail, a governor driven by said elevator car, and means actuated by said governor for causing the operation of said safety brake only when the elevator car reaches a predetermined point 10 in the elevator hatchway, in the event that the car is traveling above a predetermined speed as it arrives at said point.

18. In an elevator system, an elevator car, a guide rail therefor, a safety brake on said car operable to grip said guide rail, a governor driven by said elevator car, and means actuated by said governor for causing the operation of said safety brake when the elevator car reaches a predetermined point in 20 the elevator hatchway, in the event that the car is traveling at or above a predetermined lower than normal speed as it arrives at said point, but permitting operation of said car without causing the operation of said safety 25 brake, in the event that the car is traveling below said predetermined speed when it reaches said point.

19. In an elevator system, the combination of a safety brake on a moving part adapted 30 to cooperate with a stationary member along its path, means for applying the safety brake in the event that the moving part travels at an excessive speed, means for applying the safety brake in the event that the moving 35 part is traveling above a predetermined speed as it approaches its limit of travel, and means for applying the safety brake in the event that the moving part should pass beyond its normal limit of travel.

40 20. In an elevator system including a guide rail for the elevator car, the combination of an elevator car having a safety brake thereon adapted to be actuated to grip the elevator guide rail, governor means operative to actuate said safety brake into gripping engagement with the rail when the elevator car is traveling above a predetermined speed, and a second governor means operative at a point adjacent to the lower 45 limit of travel of the elevator car for applying said safety brake in the event that the elevator car is traveling above another predetermined speed as it approaches said limit.

50 21. In an elevator system including a guide rail for the elevator car, the combination of an elevator car having a safety brake thereon adapted to be actuated to grip the elevator guide rail, governor means operative to actuate said safety brake into gripping engagement with the rail when the elevator car is traveling above a predetermined speed, a second governor means operative at a point adjacent to the lower limit

of travel of the elevator car for applying 65 said safety brake in the event that the elevator car is traveling above another predetermined speed as it approaches said limit, and means operative below said point for applying said safety brake in the event that the 70 elevator car should travel below its normal lower limit of travel.

22. In an elevator system including a guide rail for the elevator car, the combination of an elevator car having a safety brake 75 thereon adapted to be actuated to grip the elevator guide rail, governor means operative to actuate said safety brake into gripping engagement with the rail when the elevator car is traveling above a predetermined speed, a second governor means operative at 80 a point adjacent to the lower limit of travel of the elevator car for applying said safety brake in the event that the elevator car is traveling above another predetermined speed as it approaches said limit, means operative below said point for applying said safety brake in the event that the elevator 85 travels below its normal lower limit of travel, and means in the upper portion of the elevator hatchway operative for applying the safety brake in the event that the elevator car travels above its normal upper 90 limit of travel.

23. In an elevator system including a 95 guide rail for the elevator car, the combination of an elevator car having a safety brake thereon adapted to be actuated to grip the elevator guide rail, governor means operative to actuate said safety brake into gripping engagement with the rail when the elevator car is traveling above a predetermined speed, and means in the upper portion 100 of the elevator hatchway operative for applying the safety brake in the event that the elevator car travels above its normal upper 105 limit of travel.

24. In an elevator system, an elevator car, a guide rail therefor, a safety brake on said elevator car operable to grip said guide 110 rail, means for causing the operation of said safety brake in the event that the car runs at a predetermined speed above its normal speed, and means for causing the operation of said safety brake in the event that the 115 speed of the car is not sufficiently reduced below normal as it approaches its normal limit of travel.

25. In an elevator system including a 120 guide rail for the elevator car, the combination of an elevator car having a safety brake thereon adapted to be actuated to grip the elevator guide rail, an actuating member for applying said brake, an operating member cooperative with said actuating member 125 adapted to apply the brake at any point in the travel of the car, and a second operating member adapted to be engaged by and

cooperate with said actuating member to apply the brake at a predetermined point in the hatchway.

26. In an elevator system including a guide rail for the elevator car, the combination of an elevator car having a safety brake thereon adapted to grip the elevator guide rail, said safety brake comprising a brake member supported on each side of the guide rail and adapted to be moved into engagement therewith, means for actuating said brake members into engagement with the rail, said means comprising a pair of rods one on each side of the guide rail for engaging each of the brake members, a cam engaging the outer end of each rod adapted to actuate it, a shaft carrying each cam, a gear on each shaft for actuating the members simultaneously and means for turning said shafts for applying the safety brake.

27. In an elevator system including a guide rail for the elevator car, the combination of an elevator car having a safety brake thereon, comprising a pair of pivotally mounted shoes, one on each side of the elevator guide rail and adapted to be operated into braking position with the rail by movement of the elevator car in one direction and to be released from such braking position by movement of the elevator car in the opposite direction, and means for bringing said brake shoes into contact with the rail.

28. In an elevator system; an elevator car; a guide rail therefor; and a safety brake on said car for cooperating with said rail, said safety brake comprising supporting means, one on each side of said rail, a brake shoe carried by each supporting means, and yielding means for maintaining said shoes in engagement with said rail, said shoes being mounted in their supporting means to swing in a direction upwardly and slightly away from the rail, upon the friction between the shoes and the rail exceeding a predetermined amount, against the force of said yielding means whereby the retarding force exerted by said safety brake is maintained substantially constant.

29. In an elevator system, an elevator car, a guide rail therefor, said guide rail having one thickness for one hatchway zone and a different thickness for another hatchway zone, a safety brake on said car for gripping said rail as it moves into said one hatchway zone with the car traveling in one direction, and means for causing the application of said safety brake to said rail while it is in said other hatchway zone with the car traveling in the other direction.

30. In an elevator system including a guide rail having one thickness for a portion of its length and an increased thickness for another portion of its length, an elevator

car having a safety brake thereon adapted to grip said portions of the elevator guide rail, a guide for cooperating with said rail to guide the car, said guide having shoes arranged one on each side of said rail, and resilient means for pressing said shoes toward the sides of said rail, said resilient means yielding to permit the spreading of said shoes as they pass into cooperation with the portion of the rail of increased thickness.

31. In an elevator system, a guide rail in the elevator hatchway having one thickness throughout the normal path of travel of the elevator car, and having an increased thickness for a distance above the normal path of travel of the car.

32. In an elevator system, the combination of a guide rail having a varying thickness and guide shoes mounted on the elevator car for cooperating with said rail, said guide shoes being provided with means for yieldingly pressing them toward the sides of said rail.

33. In an elevator system, a guide shoe for cooperating with the elevator guide rail, said guide shoe comprising a pair of shoes, one on each side of the rail, abutment members outside of the shoes, and springs between the shoes and said members for yieldingly holding the shoes in engagement with the rail.

34. In an elevator system, a guide shoe for cooperating with the elevator guide rail, said guide shoe comprising a supporting member carrying spring pressed shoes for yieldingly engaging the sides of the rail and a spring pressed shoe for engaging the edge of the rail.

35. A safety brake for elevators, comprising a pair of rocking jaws, means for pivotally supporting said jaws on the elevator car on opposite sides of the elevator guide rail, a brake shoe carried by each of the jaws adapted to grip said rail, and means for rocking said jaws to cause said brake shoes to engage the rail.

36. A safety brake for elevators comprising a pair of rocking jaws, means for pivotally supporting said jaws on the elevator car on opposite sides of the elevator guide rail, a brake shoe carried by each of the jaws adapted to grip said rail, means for rocking said jaws to cause said brake shoes to engage the rail, and a spring between each brake shoe and its supporting jaw adapted to exert a pressure on the brake shoe substantially parallel with the rail, whereby a substantially constant retarding force of the safety brake is maintained.

37. A safety brake for elevators comprising an abutment member on each side of the elevator guide rail, an upper and a lower stop on each abutment, a jaw pivotally connected to each of said abutments and adapt-

- ed to swing between said stops, a brake shoe between each of said jaws and said rail, links between said jaws and said shoes for connecting said shoes to the jaws and for transmitting a thrust to the shoes, springs between the upper ends of the shoes and the jaws arranged to exert a pressure on said shoes in a direction substantially parallel with the rail, rods extending through the lower ends of said abutments adapted to be actuated for rocking said jaws, springs on the rods between said abutments and the lower ends of said rods for holding the rods away from the jaws, and means adapted to raise said rods so as to actuate the jaws to a position where the brake shoes will engage the rail. 65
38. A safety brake for elevators comprising abutments on each side of the elevator 20 guide rail, a jaw member pivotally supported on each of said abutments, a brake shoe pivotally carried by each jaw member adapted to be brought into engagement with the rail by the swinging of said jaw members on their pivots, said brake members being adapted to swing upwardly on their pivots with respect to the said jaw members. 25
39. A safety brake for elevators comprising an abutment on each side of the elevator 30 guide rail, a jaw member pivotally supported on said abutments, a brake shoe pivotally carried by each jaw member so as to swing with respect to the jaw members, a spring between each shoe and its jaw member arranged to exert a pressure on said shoe in a direction substantially parallel with the rail whereby a substantially constant retarding force between the shoe and the rail is obtained when the shoes are 35 brought into engagement with the rail and means for swinging the jaw members for bringing the brake shoes into engagement with the rail. 40
40. A safety brake for elevators comprising an abutment on each side of the elevator 45 guide rail, a jaw member pivotally connected with each abutment and carrying a brake shoe adapted to engage the guide rail, and a spring stop for the jaw member carried by the supporting member. 50
41. A safety brake for elevators comprising an abutment on each side of the elevator 55 guide rail, a fixed stop on the upper portion of each abutment and a spring stop on the lower portion of each abutment, a jaw member pivotally carried by the abutment and adapted to swing between said stops, an actuating rod for each jaw member adapted to engage the member and swing it upwardly, a brake shoe pivotally carried by each 60 jaw member, a spring between each jaw member and its brake shoe adapted to exert a substantially constant retarding force between the jaw member and rail when the jaw member is swung upwardly for bringing the brake shoe into engagement with the rail. 65
42. A safety brake for elevators comprising an abutment on each side of the elevator 70 guide rail, a jaw member carried by each abutment, said jaw members each having a recess providing a seat and a stop in the jaw along the lower surface of the recess, a brake shoe between each jaw member and the rail, said brake shoes each having a recess providing a seat, a link positioned with its ends in said recesses in pivotal relation therewith, pivot pins extending through the ends of the links affording connections between the jaws and brake shoes and a 75 spring between each jaw member and the pivot extending through the brake shoe connected therewith for yieldingly retaining the brake shoe outward from the jaw member and the link in engagement with the stop at 80 the bottom of the recess in the jaw member. 85
43. In an elevator system including a guide rail for the elevator car, the combination of an elevator car having a safety brake thereon adapted to be actuated to grip the 90 elevator guide rail, means for actuating said safety brake into gripping engagement with the rail when the elevator car is traveling downwardly, means for automatically releasing said safety brake after such an application to the rail by a reverse movement of the elevator car, and means for applying said safety brake to the rail in the event that the elevator car travels above a predetermined point and for locking it in such 95 applied position. 100
44. In an elevator system, a moving part having a safety brake thereon adapted to be applied and act with one retarding force when the moving part is operating in one 105 direction and to be applied and act with a different retarding force when the moving part is operating in the other direction. 110
45. In an elevator system the combination of a moving part having a safety brake 115 thereon, means for applying the safety brake, means for regulating the retarding force with which the safety brake will be applied when the moving part is operating in one direction, and means for regulating the retarding force with which the safety brake will be applied when the moving part is operating in the other direction. 115
- In testimony whereof, I have signed my name to this specification.

DAVID L. LINDQUIST.
